UNITED STATES PATENT OFFICE.

GEORGE A. LIPPINCOTT, OF PHILADELPHIA, PENNSYLVANIA.

DESIGN FOR A LAMP SHADE.

Application filed May 2, 1925. Serial No. 13,308. Term of patent 3½ years.

To all whom it may concern:

Be it known that I, GEORGE A. LIPPINCOTT, a citizen of the United States, residing at Philadelphia, county of Philadelphia, State of Pennsylvania, have invented a new, original, and ornamental Design for Lamp Shade, of which the following is a specification, reference being had to the accompanying drawing, forming a part thereof.

Figure 1 is a perspective view of a lamp shade, showing my new design. Figure 2 is a top plan view of the invention.

I claim:

The ornamental design for a lamp shade, as shown.

GEORGE A. LIPPINCOTT.
